UNITED STATES PATENT OFFICE.

ALLEN A. FULLER, OF BIRMINGHAM, ALABAMA, ASSIGNOR OF ONE-HALF TO C. M. McCRUM, OF BIRMINGHAM, ALABAMA.

AUTOMATIC SAFETY STOPPING DEVICE FOR ELEVATORS.

1,148,450.

Specification of Letters Patent.

Patented July 27, 1915.

Application filed April 3, 1914. Serial No. 829,381.

To all whom it may concern:

Be it known that I, ALLEN A. FULLER, a citizen of the United States of America, residing at Birmingham, in the county of Jefferson and State of Alabama, have invented certain new and useful Improvements in Automatic Safety Stopping Devices for Elevators, of which the following is a specification.

10 My invention relates to safety appliances for elevators and its object is to utilize any relative movement that may take place from any cause between the elevator car and its governor cable to effect a quick application 15 of brakes to stop the car without the emergency clamp on the car being brought into service.

I have found in practice that the governor cable becomes blocked in its travel with the 20 car from various causes, such as where a broken strand of the cable catches in the openings in the pent house floor; where rags or like matters are caught in the pit sheave for the governor cable; or where the cable 25 jumps the governor sheave. In any of these events the clevis on the governor cable is jerked loose from the cable clamp on the top of the car and proceeds to pull on a cable which leads to the drum on the bottom of 30 the car and unwinds it to apply the emergency clamps.

According to my invention, as soon as the governor cable is blocked for any reason, or breaks, its resulting movement, relative 35 to the car actuates means which cause the application of brakes which act on the car hoisting means in ample time to stop the car before the emergency clamps under the car go into operation.

40 My invention also comprises the details of construction and arrangement of parts which are illustrated in their preferred embodiment only in the accompanying drawings, and which are hereinafter more particularly described and claimed, in which:—

Figure 1 is a vertical sectional elevation of a car looking toward the front. Fig. 2 is a diagrammatic view showing in part the circuit connections controlled by my automatic switch which is shown in plan view. Fig. 3 is a vertical sectional view through the switch casing showing the switch in its several operating positions.

Similar reference numerals refer to similar parts throughout the drawings.

Referring to the preferred embodiment of my invention illustrated in the accompanying drawings, I show an elevator 1, connected to hoist cables 2, and guided as it is raised and lowered in its shaft by side rails 3. 60 The car is provided with the usual form of clutch 4 which frictionally engages a clevis 5 connected to the endless governor cable 6. A slack cable 7 is also attached at one end to the clevis and its other end is passed around pulleys in a bearing frame 8, fast to the cross beam 9 at the top of the elevator, and around a pulley 10 at the bottom of the car and connected to the drum 10^a of the usual emergency clamp mechanism. This 70 cable is adapted to act in the well known manner to turn the drum and force the emergency clamp mechanism to engage the guide rails 3 and stop the car. The governor cable 6, by means of the clutch 4 is caused 75 to travel with the car and in doing so it passes around a sheave 11 in the pent house and over a sheave 12 in the pit. The sheave 11, as it is turned by the governor cable, acts through suitable connections to drive a governor 13 adapted, in the well understood manner, to apply the brakes and stop the car under excessive speed conditions. The car may be equipped with any suitable control mechanism such as the car switch 14 and 80 the emergency switch 15.

I have illustrated in Fig. 2 diagrammatically a part of a standard arrangement of circuit connections and control mechanism now commonly in use but it will be understood that such arrangement forms no part of my present invention and may be widely varied in accordance with the conditions of and requirements for each installation. In the arrangement illustrated, the supply mains lead to the points 16 and 17 for the circuit breaker switch 18. From one leg of this switch the positive wire 19 leads to general control mechanism, not shown, and has a branch 20 leading through switches normally closed but which are controlled by the governor 13 and the limit switch magnets 21, to the magnet 22 which, when energized, holds the circuit breaker switch 18 in closed position. The wire 20 continues to the emergency switch 15 and there branches, one leg 23 leading to the negative main 24 and the other leg 25 to the car switch 14 from which the various circuit wires lead to the control mechanism. The armature 26 of the 95 100 105 110

motor which moves the hoist cables, has a coil 27 thereof connected in a circuit 28 normally open circuited at the contacts 29 which are arranged to be closed by the circuit breaker switch 18 when the latter opens responsive to the deenergizing of the coil 22 by the opening of either limit switch 21 or the governor controlled switch 13, or the emergency switch 15 on the car. When the circuit 28 is closed the armature 26 is short circuited and acts as a magnetic brake in conjunction with the other brakes to quickly stop the car.

My automatic safety stop switch is preferably interposed in the circuit 20 in which the magnet 22 and both car switches 14 and 15 are included, and comprises an insulated base 30 having spaced contacts 31 thereon adapted to receive between them a knife switch 32. The switch 32 is mounted on a shaft 33 which turns in suitable bearings 34 which are preferably disposed in a box or casing 35 that is attached to the elevator car at any suitable point, preferably within the car opposite the governor cable. The shaft 33 projects without the box and carries on its outer end a crank arm 36 bifurcated at its end to form spaced arms 37 which straddle one side of the endless governor cable. I make fast on the cable clamps 38 and 39 which are disposed closely together, one above and the other below the arms 37. The arrangement of parts is such that any relative movement between the car and the cable 6, which is greater in amount than the play allowed in the detachable connection between the clutch 4 and clevis 5, will cause one or the other of the clamps 38 and 39 to engage the crank 36 and turn it to swing the knife switch 32 from position between the contacts 31, thereby opening the circuit 20 both to the circuit breaker coil 22 and both car switches, thereby causing the immediate application of all brake means which act through the hoist cables 2 to stop the car. All brake means so acting are what I term the normal brakes, though they include the emergency brake effected by the short circuiting of the armature and the resulting conversion of the motor into a brake. The clamps 38 and 39 are preferably so arranged that in the manner described they will effect the stopping of the car before a sufficient relative movement shall have taken place between the car and cable 6 to take up the slack cable 7 and cause the application of the clamps under the car. The clamps will ride past the arms 37 and clear the lever after opening the knife switch. Also in the event the cable breaks its weight will be sufficient to jerk the knife switch 32 open and apply the emergency brakes, though under such conditions the clamp mechanism could not be applied. Further, by my preferred arrangement of the clamps

the car is stopped before it accumulates a momentum and in this respect it operates to minimize the damage both to the car and its guide rails when the governor cable becomes blocked or broken. The opening of my automatic stop means has the same effect as the opening of the emergency switch 15 and it constitutes in effect a second and automatic emergency switch. This duplication of the emergency switches is adopted solely on the grounds of convenience of location of the two switches and the adaptation of my invention to elevators now in service.

While it is my desire to have the circuit connections controlled by the opening of my automatic safety switch cause the application of the several brake means which normally act on the car hoisting means to stop the car, yet it will be understood that any one or more of such ordinary braking means may be thrown into operation by the opening of the safety switch and I do not therefore desire to limit myself in respect to the character of the brake controlled by the switch. I regard the construction as preferred however in which the braking means will be effective to arrest the car before the emergency clamps carried by the car shall have been disturbed or at least sufficiently actuated to go into service or require resetting.

When I refer to normal brake means I mean merely to distinguish between such means as are now used to act on the hoist means to stop the car and the emergency stop means which are carried by the car itself and which, when they go into service, are very violent in their action and liable to cause injury or damage.

Obviously, the mechanical means by which relative movement between the car and the cable is transmitted to operate the switch may be widely varied without departing from the spirit of my invention.

Having thus described my invention, what I claim as new and desire to secure by Letters Patent, is:—

1. The combination with an elevator, hoist means therefor, normal brake means which act on the hoist means for the car, emergency brake mechanism carried by the car, a governor cable detachably connected to the car, an operating connection from said cable to said emergency brake mechanism on the car, electric mechanism for controlling said normal brake having circuit connections to the car, and a switch in said circuit connections, which switch is connected to said cable so as to be opened by any substantial movement thereof relative to the car and apply the normal brake in advance of any movement imparted by the cable to said emergency brake mechanism.

2. The combination with an elevator and its hoist and normal brake mechanism, of an

emergency mechanical brake attached to the car, electrical means which control the normal brake and comprise a controller switch on the car, a governor cable, and operating 5 connections from said cable to both said switch and said mechanical brake, said connections being such as, upon relative movement between the elevator and said cable, to open the switch independently of and in advance of the operation of said emergency 10 mechanical brake.

3. The combination with an elevator, hoist means therefor, a hoist brake, a governor cable therefor and normally movable therewith, electrically controlled mechanism for controlling the hoist brake for the elevator, said mechanism comprising circuit connections and a switch mounted on the car, a lost-motion connection between said switch 15 and governor cable for operating the switch by means of said cable when it breaks or moves bodily in either direction relatively to the car, and means controlled by the operation of said switch to apply the hoist brake.

20 4. In combination, an elevator car, a governor cable, a switch mounted on said car, means to operate the switch comprising a bifurcated arm which straddles the governor cable, and lugs on the governor cable above and below said arm, said switch being operable by either of said lugs when relative 25 movement takes place between the car and

cable, and electrical mechanism controlled by said switch for effecting an emergency application of the brakes to the car. 35

5. The combination with an elevator car and emergency stop mechanism carried thereby, of a governor cable, means controlled thereby to operate said emergency stop mechanism, hoist mechanism for the 40 car, brake means acting on said hoist mechanism to stop the car, control mechanism on the car for releasing and applying said brake means under normal operating conditions, and means also controlled by said governor 45 cable and adapted to throw said brake means into service independently of said emergency stop mechanism and of said normal brake control mechanism.

6. In combination, an elevator car, a governor cable, a switch mounted on said car, means to operate the switch comprising a switch arm, and means on the governor cable adapted to shift said arm in either direction 50 when relative movement takes place between the car and cable, and electrical mechanism controlled by said switch for effecting an emergency application of brakes to the car.

In testimony whereof I affix my signature in presence of two witnesses.

ALLEN A. FULLER.
